No. 36,930.

Patented May 24, 1904.

UNITED STATES PATENT OFFICE.

SIDNEY A. KELLER, OF NEW YORK, N. Y., ASSIGNOR TO MARCUS T. GOLDSMITH, OF NEW YORK, N. Y.

DESIGN FOR A HANDLE FOR MIRRORS, BRUSHES, OR LIKE TOILET ARTICLES.

SPECIFICATION forming part of Design No. 36,930, dated May 24, 1904.

Application filed April 27, 1904. Serial No. 205,245. Term of patent 7 years.

To all whom it may concern:

Be it known that I, SIDNEY A. KELLER, a citizen of the United States, and a resident of the city of New York, borough of Manhattan, in 5 the county and State of New York, have invented a new, original, and ornamental Design for a Handle for Mirrors, Brushes, or Like Toilet Articles, reference being had to the accompanying drawings, in which—

10 Figure 1 is a face view of a handle, showing my design; and Fig. 2 is a side elevation of the same.

I claim as new and desire to secure by Letters Patent—

The ornamental design for a handle for mirrors, brushes and like toilet articles herein shown. 15

SIDNEY A. KELLER.
